Attest.

Reverend

W. R. Edelen.

Inventor

Stephen D. Field
by J. L. Edwards
his attorney.

b is not pivoted, but is supported by a yielding strap or spring *f*.

In either of these improved forms the lever *b* is free to move longitudinally, whereby the 5 sliding of the levers on each other is avoided and the consequent friction is eliminated. The friction is then only that of the curved surface of lever *a* rolling upon lever *b*. The device is thus rendered more sensitive, and 10 becomes capable of responding to feeble forces.

I claim as my invention—

1. In a system of compensating levers, a 15 pair of levers arranged substantially parallel and having abutting faces, one of said faces being curved, and a support for one of the levers adapted to permit longitudinal movement thereof, as described.

2. The combination with a pair of compensating levers arranged substantially parallel 20 and having abutting faces, one of said faces

being curved, of a spring or yielding strap forming the support of one of the levers to permit longitudinal movement of the lever, as described.

3. The combination with an electro-magnet and its armature, of a pair of compensating levers, whereby a constantly increasing resistance is opposed to the attraction of the magnet upon its armature, one of said levers 30 being mounted upon a support permitting longitudinal movement of said lever, substantially as described.

In testimony whereof I have signed my name to this specification, in the presence of two subscribing witnesses, this 24th day of July, 1895.

STEPHEN D. FIELD.

Witnesses:

FRANK R. MCBERTY,
FRANK C. LOCKWOOD.
